CABINET

John L. Gianfagna, Staten Island, N.Y., assignor to
Sperry Rand Corporation, New York, N.Y., a cor-
poration of Delaware

Filed Oct. 18, 1967, Ser. No. 9,052

Term of patent 14 years

Int. Cl. D6—01

U.S. Cl. D33—19

FIG. 1.

FIG. 2.

FIG. 3.

FIG. 4.

FIG. 1 is a front perspective view of a cabinet showing my new design;

FIG. 2 is a top view thereof;

FIG. 3 is a rear elevational view thereof; and

FIG. 4 is an elevational view of one of the two identical sides.

The essential features of my design reside in those portions shown in full lines on the drawing.

I claim:

The ornamental design for a cabinet, substantially as shown and described.
